CIRCUIT CONTROLLING DEVICE

Clarence W. Kuhn, Milwaukee, Wis., assignor to
Cutler-Hammer, Inc., Milwaukee, Wis., a corporation of Delaware

Application June 9, 1933, Serial No. 675,011

9 Claims. (Cl. 200—81)

This invention relates to electric circuit controlling devices, and is particularly applicable to control devices for motor driven apparatus such as electric refrigerators.

5 My copending application Serial No. 514,363, filed February 9, 1931, discloses a control device for electric refrigerators having a single control knob associated therewith which is manually adjustable to effect temperature control, defrosting 10 and overload reset. The unit control feature of this device has been found very desirable but in some instances this device has been found objectionable due to the fact that it is necessary to employ a signal lamp to indicate tripping of the 15 overload mechanism.

The present invention has among its objects to provide a refrigerator controller having a manual control adapted to indicate tripping of the overload mechanism, and adjustable to effect temperature control, defrosting and overload reset.

20 Another object is to provide a control device of the aforementioned character having a rotatable temperature control knob which is moved axially out of a given normal position to indicate tripping of the overload mechanism and 25 which is returnable to such position to effect resetting of the overload mechanism.

Another object is to simplify and generally improve the construction and operation of refrigerator control devices and to provide improved manual control means therefor.

Various other objects and advantages of the invention will hereinafter appear.

The accompanying drawings illustrate certain embodiments of the invention which will now be described, it being understood that the embodiments illustrated are susceptible of modification without departing from the spirit and scope of the appended claims.

40 In the drawings,

Fig. 1 is a plan view of a control device embodying the invention, a cover for the enclosing casing of the device being removed;

45 Figs. 2, 3 and 4 are sectional views taken substantially on lines 2—2, 3—3 and 4—4, respectively, of Fig. 1;

Fig. 5 is a fragmentary sectional view similar to that shown in Fig. 2, but illustrating certain of the operating parts in another position;

50 Fig. 6 is a sectional view on line 6—6 of Fig. 2;

Fig. 7 is a sectional view on line 7—7 of Fig. 1;

Fig. 8 is an isometric view of a movable switch element associated with the switch unit shown in 55 Fig. 1;

Fig. 9 is an isometric view of the complete switch unit together with a diagrammatic showing of the circuit connections therefor;

Fig. 10 is a sectional view on line 10—10 of Fig. 1, and

Fig. 11 is a sectional view illustrating a modified form of manual control embodying the invention.

The controller illustrated in Figs. 1 and 2 includes an elongated box-shaped housing 1 having a switch unit 2 and a fluid condition responsive unit 3 mounted therein. As hereinafter set forth, the switch unit 2 is controlled by the fluid condition responsive unit 3 to effect starting and stopping of the refrigerator and the unit 10 3 is so adjusted to provide predetermined normal cycles of operation of the refrigerator and is also adjustable by rotation of a knob 4 mounted on the housing 1 to provide for modification of such cycles. Also as hereinafter set forth the 20 switch unit 2 has an overload mechanism associated therewith which is responsive to effect stopping of the refrigerator and the knob 4 is movable axially to control such mechanism and to also indicate response thereof under over- 25 load conditions.

The switch unit 2 includes an insulating block 5 having stationary contacts 6 and 7 mounted upon the front end thereof to be bridged by a pair of cooperating movable contact members 8 and 9. As shown in Fig. 9 one end of movable contact 8 cooperates with stationary contact 6 and the opposite end thereof is pivotally mounted at 10 upon an inverted L-shaped supporting member 11 which is secured to the upper face of insulating block 5 by a screw 12. Also as shown in Fig. 9, the movable contact 9 is mounted upon an insulating support 13 and one end thereof cooperates with stationary contact 7 while the opposite end thereof cooperates with movable contact 8 at a point to the right of pivot 10. Insulating support 13 is slidable within a recess 14 in the underside of insulating block 5 and contact 9 is mounted between spaced upwardly projecting lugs 15 and 16 on the front end of said support. 45 As shown in Figs. 6 and 8, contact 9 has a stirrup 17 secured to the rear face thereof which straddles lug 16 and a coil spring 18 held under compression between the inner end of said stirrup and said lug serves to bias said contact towards said lug. Insulating support 13 has an overload responsive mechanism associated therewith for normally holding the same in the position shown in Fig. 6 against the action of a spring 19 which engages an upwardly projecting lug 20 on the rear

end of said support. As is apparent, with the support 13 held in the position shown in Fig. 6 spring 18 acts to yieldingly hold movable contact 9 in engagement with stationary contact 7 and movable contact 8 and to also yieldingly hold the latter contact in engagement with stationary contact 6.

The overload responsive mechanism associated with insulating support 13 includes a spring latch 10 22 secured to said support and arranged to cooperate with an electro-thermal device 23 mounted upon insulating block 5. Electro-thermal device 23 includes an electric heater 24 of helical form arranged within a recess in the upper face 15 of insulating block 5, a tubular member 25 fixed within an opening in said block and having its upper end surrounded by said heater and a ratchet pin 26 located within said tubular member. The upper end of ratchet pin 26 is connected to tubular member 25 by a solder connection 27 and the lower end of said pin is supported upon a plate 28 fixed to base 5 by a screw 29 and is provided with an enlarged toothed head 30 which cooperates with latch 22 to normally hold the insulating support 13 in the position shown in Fig. 6 against the action of spring 19. As shown in Fig. 9, the heater 24 has one terminal connected to contact 6 and the other terminal thereof is connected to a terminal plate 31 fixed to the 20 upper face of insulating base 5 by a rivet 32 shown in Fig. 2. A line terminal 33 is also mounted upon the upper face of insulating base 5 and contact 7 is secured to base 5 and connected to said terminal by a screw 34.

35 The refrigerator motor is illustrated at M in Fig. 9 and the supply circuit therefor is indicated by lines L¹—L². Line L¹ is connected to terminal 33 and one terminal of motor M is connected to terminal plate 31 while the opposite terminal thereof is connected directly to line L². With the insulating support 13 latched in the position shown in Fig. 6 the motor circuit is normally established from line L¹ to terminal 33 through screw 34 to stationary contact 7 through movable contacts 9 and 8 to stationary contact 6 and through heater 24 and terminal plate 31 to one terminal of the motor M. Upon given overload conditions in the motor circuit, heater 24 acts to fuse the solder connection 27 of the electro-40 thermal device 23, and as is apparent the toothed wheel 30 of said device is then released and insulating support 13 is moved forwardly under the action of spring 19 to move contact 9 out of engagement with stationary contact 7 and movable contact 8 for interruption of the motor circuit. As will now be set forth, the knob 4 is adjustable axially to effect resetting of the aforescribed overload responsive mechanism and to also effect tripping thereof at will for defrosting of the refrigerator.

60 As shown in Fig. 2, the knob 4 is arranged within a ring projection 35 on the front end of housing 1 and is slidably mounted upon a sleeve 36 supported within an opening in the front wall 65 of said housing. A pin 37 swiveled to the knob 4 by a screw 38 is arranged within the opening in sleeve 36 and a spring 39 held under compression between a shoulder formed on the interior of said sleeve and an enlarged head 40 on the rear end 70 of said pin serves to yieldingly hold said head in engagement with the front end of insulating support 13. The insulating base 5 of switch unit 2 is secured to the bottom wall of housing 1 by screws 41 and 42 (Fig. 1) and is so located that 75 under normal conditions knob 4 is held in the

position shown in Fig. 2 under the action of spring 39. As hereinbefore set forth, upon response of the above described overload mechanism the insulating support 13 moves forwardly under the action of spring 19, and as is apparent pin 37 moves therewith and causes knob 4 to move forwardly with respect to the ring projection 35 on housing 1 to indicate response of said overload mechanism. Upon inward movement of knob 4 into the position shown in Fig. 2 insulating support 13 is moved inwardly by the pin 37 to effect resetting of the overload mechanism.

Knob 4 is also provided with means for manually tripping the aforescribed overload mechanism to effect defrosting of the refrigerator. 15 Such means comprises an insulating trip member 44 reciprocably mounted upon insulating support 13 and secured to the inner end of pin 37. As shown in Figs. 2 and 8, the trip member 44 has a projection 45 on the inner end thereof which is 20 located to the left of spring latch 22 (Fig. 6) and is guided within a recess 46 in the upper face of insulating support 13. Upon forward movement of knob 4 out of the position shown in Fig. 2 the projection 45 on trip member 44 engages the 25 spring latch 22 to release the same from the toothed head 30 and insulating support 13 then moves forwardly under the action of spring 19 to cause contact 9 to effect interruption of the motor circuit for defrosting of the refrigerator. 30

As hereinbefore set forth the energizing circuit for the driving motor of the refrigerator extends through stationary contact 6 and movable contact 8, and as will now be set forth the fluid condition responsive unit 3 acts upon said movable contact to effect cyclic operation of the refrigerator.

The fluid condition responsive unit 3 includes a bellows 48 secured to the rear wall of housing 1 and having a communicating pipe extension 49 40 on the rear end thereof. The pipe 49 may be connected to the low pressure side of the refrigerator to provide for operation of the bellows by pressure in that part of the apparatus, or it may contain an expansible gas and be arranged at a 45 point contiguous to the refrigerating apparatus where the temperature and consequently the pressure within the pipe and the bellows varies in accordance with operations of the refrigerator. The front end of bellows 48 cooperates with a piv- 50 oted lever 50 having an adjustable spring 51 associated therewith which opposes expansive movements of the bellows, and said lever has a snap operating mechanism associated therewith for effecting operation of the movable contact 6. 55

More specifically lever 50 is pivotally mounted upon a pin 52 carried by a U-shaped bracket 53 fixed to the bottom wall of housing 1 by screws 54. Said lever has a stirrup 55 fixed to the rear face thereof which bears against the outer end of 60 bellows 48 and carries a snap operating mechanism comprising a pair of oppositely arranged U-shaped members 56 and 57 operatively connected by a tension spring 58. As shown in Figs. 65 2, 4 and 5, the side arms of members 56 are pivoted at 59 upon spaced legs 60—60 associated with stirrup 55, while the side arms of member 57 are pivoted at 61 upon spaced legs 62—62 associated with said stirrup. Also as shown in these figures the side arms of bracket 53 are each 70 provided with a pair of spaced pins 63—63 for engaging member 57 on opposite sides thereof and said bracket is also provided with a fixed stop 64 for limiting movement of member 56 in one direction and an adjustable stop 65 for lim- 75

iting movement thereof in an opposite direction. The free end of member 56 cooperates with an insulating strip 66 slidably mounted within a slot in the upper face of insulating base 5, and as shown in Fig. 9 the front end of said strip is operatively connected to contact 8 at 67.

The operation of the aforescribed fluid condition responsive unit will now be more fully described. With lever 50 in the position shown in Fig. 2 member 57 is held in a position wherein the axis of spring 58 is located to the left of the pivot 59 of member 56 and said spring thus acts to hold member 56 in engagement with its associated stop 65. With member 56 in this position movable contact 8 engages its cooperating stationary contact 6 to establish an energizing circuit for the refrigerator driving motor as hereinbefore set forth. With the driving motor in operation the temperature within the refrigerator decreases and upon a predetermined temperature drop determined by the degree of compression of spring 51 bellows 48 permits lever 50 to move inwardly under the action of said spring towards the position shown in Fig. 5. During such inward movement of lever 50 the pins 63 on bracket 53 cause the member 57 to assume a position wherein the axis of spring 58 is located to the right of the pivot 59 of member 56, and said spring then acts to move member 56 with a snap action from the position shown in Fig. 2 into the position shown in Fig. 5. Upon movement of member 56 into the position shown in Fig. 5 insulating strip 66 is moved forwardly to disengage movable contact 8 from stationary contact 6 for stopping of the refrigerator. The temperature within the refrigerator then increases and upon a predetermined temperature increase bellows 48 moves lever 50 forwardly against the action of spring 51 into a position wherein the pins 63 on bracket 53 cause member 57 to assume a position wherein the axis of spring 58 is located to the left of the pivot 59 of member 56. Spring 58 then returns member 56 with a snap action into the position shown in Fig. 2 and contact 8 reengages stationary contact 6 to effect restarting of the refrigerator.

As will now be set forth, spring 51 has a shop adjustment and a user's adjustment associated therewith for determining the temperature values at which the refrigerator is started and stopped. As shown in Fig. 2, the front end of spring 51 engages a nut 68 which is threaded into one leg of a U-shaped bracket 69 slidably mounted within a channel 70 in the bottom wall of housing 1. The other leg of bracket 69 has a threaded opening therein for receiving an enlarged screw threaded portion 71 on the inner end of sleeve 36 which abuts a washer 72 mounted in the front wall of housing 1. As hereinbefore stated, knob 4 is movable axially upon the sleeve 36, and as shown in Fig. 10 said sleeve is provided with flat side faces which engage within the opening in knob 4 to lock said sleeve and said knob against relative rotation. Also as shown in Figs. 2 and 10, the inner face of knob 4 is provided with a channel 73 for receiving a projection 74 on the front face of housing 1, and a stop 75 within said channel cooperates with the projection 74 to limit rotation of said knob in opposite directions. As is apparent from the foregoing, the degree of compression of spring 51 may be varied by adjusting nut 68 with respect to bracket 69, and in practice this nut is shop adjusted with sleeve 36 in a given angular position to provide for starting and stopping of the refrigerator at

predetermined temperature values to effect what may be termed normal cycles of operation of the refrigerator. By rotating knob 4, the screw 71 on sleeve 36 varies the position of bracket 69, and the degree of compression of spring 51 is thus changed to vary the temperature values at which the refrigerator is started and stopped, or to effect what may be termed non-normal cycles of operation of the refrigerator.

As shown in Fig. 2, the biasing spring 19 associated with insulating support 13 is held under compression between said support and a thimble 16 fixed within an opening in nut 68. Also as shown in Fig. 2, the aforescribed mechanism is enclosed within the housing 1 by a cover 77 which is secured to said housing by a screw 78.

Referring now to Fig. 11, the same illustrates a modified form of manual control means including a knob 79 fixed to the sleeve 36, and a knob 80 fixed to the pin 37. As is apparent, knob 79 when rotated serves to adjust the sleeve 36 to vary the temperature values at which the refrigerator is started and stopped. On the other hand, the pin 37 is movable axially by the knob 80 to effect control of the switch unit 2 in the manner hereinbefore set forth, and to also indicate tripping of the aforescribed overload mechanism.

What I claim as new and desire to secure by Letters Patent is:

1. In a controller for electric refrigerators, in combination, a circuit controlling device, fluid condition responsive means for effecting cyclic operation of said device, thermal overload means responsive to effect circuit opening operation of said device, and a manual control element rotatable to vary the operating characteristic of said first mentioned means and movable axially to effect resetting of said thermal overload means upon response thereof.

2. In a controller for electric refrigerators, in combination, a circuit controlling device having thermal overload means associated therewith responsive to effect circuit opening operation thereof, fluid condition responsive means for effecting cyclic operation of said device and a manual control element rotatable to vary the operating characteristic of said fluid condition responsive means, said manual control element being also movable axially to effect operation of said device independently of said fluid condition responsive means and to effect resetting of said thermal overload means upon response thereof.

3. In a controller for electric refrigerators, in combination, a circuit controlling device having thermal overload means associated therewith responsive to effect circuit opening operation thereof and having fluid condition responsive means associated therewith for effecting cyclic operation thereof, and a manual control element rotatable to vary the operating characteristic of said last mentioned means, said control element being also movable axially out of a given normal position upon response of said overload means and being adapted upon return to said normal position to reset said overload means.

4. In a controller for electric refrigerators, in combination, means for starting and stopping operation of the refrigerator to obtain normal cycles of operation, overload protective means for non-normally stopping operation of said refrigerator, and means including a single manual control element rotatable to secure temporary modification of the normal cycles of operation

of said refrigerator, and movable axially to effect resetting of said overload protective means.

5. In a controller for electric refrigerators, in combination, a circuit controlling device having thermal overload means associated therewith responsive to effect circuit opening operation thereof, fluid condition responsive means for effecting cyclic operation of said device, said means having a manual control element associated therewith rotatable to vary the operating characteristic thereof, and means for moving said manual control element into a given position to indicate response of said thermal overload means and for also effecting resetting of said thermal overload means by movement of said manual control element out of such position.

6. In a controller for electric refrigerators, in combination, an enclosing casing, a circuit controlling device mounted within said casing and having thermal overload means associated therewith for effecting circuit opening operation thereof, a fluid condition responsive device also mounted within said casing and associated with said circuit controlling device to effect cyclic operation thereof, and a pair of concentrically arranged adjusting parts mounted upon said enclosing casing, one of said adjusting parts being associated with said fluid condition responsive device and being rotatable to vary the operating characteristic thereof and the other of said adjusting parts being associated with said circuit controlling device and being movable axially to trip said thermal overload means and to effect resetting thereof.

7. In a controller for electric refrigerators, in combination, a circuit controlling device, thermal overload means associated therewith responsive to effect circuit opening operation thereof, fluid condition responsive means for effecting cyclic operation of said device and adjusting means in-

cluding a manual control element movable in a given plane to vary the operating characteristic of said fluid condition responsive means, said control element being also movable in another plane to effect operation of said device independently of said fluid condition responsive means and to effect resetting of said thermal overload means upon response thereof.

8. In a controller for electric refrigerators, in combination, a circuit controlling device, thermal overload means associated therewith responsive to effect circuit opening operation thereof, fluid condition responsive means for effecting cyclic operation of said device and a pair of concentrically arranged adjusting parts, one of said adjusting parts being movable in a given plane to vary the operating characteristics of said fluid condition responsive means and the other of said adjusting parts being movable in a different plane to effect operation of said device independently of said fluid condition responsive means and to also effect resetting of said thermal overload means upon response thereof.

9. In a controller for electric refrigerators, in combination, a circuit controlling device, thermal overload means associated therewith responsive to effect circuit opening operation thereof, fluid condition responsive means for effecting cyclic operation of said device and adjusting means for varying the operating characteristic of said fluid condition responsive means, said adjusting means including a manual control element movable into a given position to effect circuit opening operation of said device at will, said element being also movable into said given position to indicate response of said thermal overload means and being movable out of such position to effect resetting of said thermal overload means.

CLARENCE W. KUHN. 40
